(57) **CLAIM**

The ornamental design for a bank-note checking machine.

DESCRIPTION

FIG. 1 is a front, top, right side perspective view of a bank-note checking machine, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is an enlarged cross sectional view thereof, taken along line 8-8 in FIG. 2; and,

FIG. 9 is another enlarged cross sectional view thereof, taken along line 9-9 in FIG. 7.

The broken lines in FIGS. 1, 2, 8 and 9 form no part of the claimed design.
